UNITED STATES PATENT OFFICE.

GEORGE B. FOX AND JOE G. CHRISTIAN, OF WOLCOTT, NEW YORK.

COUNTING MECHANISM FOR PARING MACHINES.

Application filed January 28, 1926. Serial No. 84,449.

The object of this invention is to provide a counting mechanism and means for ready attachment to a certain part of the operating mechanism of an apple paring machine so that the number of apples placed on the forks of the machine and pared thereby are automatically counted and their number compared with the rated capacity of the machine.

10 This and other objects of this invention will be fully illustrated in the drawing, described in the specification and pointed out in the claim at the end thereof.

In the accompanying drawing:

15 Figure 1 is a perspective view of a portion of an apple paring machine and the counter attached thereto illustrating the particular mechanism for operating the counter.

20 Figure 2 is a front elevation of the counter and its operating mechanism.

Figure 3 is a top plan view of the counter and its operating mechanism.

In the several figures of the drawing like reference numerals indicate like parts.

Apple paring machines are operated at a rated capacity. This capacity of course varies with each operator who feeds a machine. Some are slower and others faster. 30 As long as an operator conscientiously performs his or her work in operating the machine that is feeding apples to the machine as fast as he or she can, it is all that can be asked for. In many cases, however, one 35 or more of the operators shirk their duty and instead of feeding apples to the machine they allow it to run idle. The paring machine operates the same whether apples are pared by it or not and the R. P. M. of each 40 machine therefore does not necessarily give the output of the machine or even approximately so, and unless the operator is watched there is no way in which the output of each individual operator and its machine can be 45 checked as the apples after being pared are placed into a common receptacle or are passed onto the slicing machine for slicing preparatory to their being dried.

The invention forming the subject matter 50 of our present invention is to provide a counter that co-operates with a part of the mechanism of the apple paring machine so that it only counts the productive turns of

this particular mechanism and ignores all other movements thereof.

The particular mechanism to which the counter and its operating mechanism is applied is illustrated in Figure 1, and comprises the rotating forks and their operating mechanism. There are at the present 55 time many different types of apple paring machines on the market but many or all of them use similar rotating forks 1, 1 by means of which the apples are fed to and held against the paring knife. Two or more of 60 these rotating forks are grouped and mounted on a rotating frame 2 so that while the apple on one of the forks is presented to the paring knife the other or others are ready 65 to receive another apple.

The frame 2 is mounted to rotate on the spindle 3 and each rotating fork is provided with a pinion 4 at one end thereof through which it is rotated on presenting the apple to the paring knife. The forks 1 have a hollow center in which the sliding rod 4 is mounted. This rod extends from one end of the fork to the other. At the rear end the rod is provided with the head which serves as a stop for the movement of the rod in one 70 direction. This rod is provided to expel the core of the apple that remains in the fork after the apple has been pared and it is the movement and position of this rod which is made to co-operate with the operating mechanism of the counter in order to count the 75 apples actually pared by the paring machine.

Whenever an apple is forced onto one of the forks 1, the core of it enters the hollow center of the fork. In doing so it forces the 80 sliding rod 4 out of the front portion of the fork so that the rear thereof with the head 85 projects into the cam groove provided in the side of the apple paring machine. The end of the sliding rod remains in this position until the apple is peeled or pared and the apple is taken off from the fork. When 90 this has taken place and the frame 2 is rotated to allow another apple to be placed onto the fork the end of the sliding rod is 95 forced back into the fork by the inclined cam 8. In doing so the core of the apple is forced out of the fork and is then ready to receive the next apple.

Only when an apple is placed onto the 100 fork is the end of the sliding rod forced out

of the end of the fork and when therefore no apple is placed onto the fork the sliding rod remains inside of the fork and the movement of the paring machine does not operate the counter. The counter 10 proper may be a stock counter and provided with a crank 11. This crank is connected by means of the spring 12 to the swinging lever 13 pivoted on the stud 14. The stud 14 and counter 10 are suitably supported on the U shaped bracket 15 which in turn is clamped to the frame of the apple paring machine by means of the set screw 16. This set screw is threaded into the side of the U shaped bracket and when tightened against the outside of the frame of the machine firmly clamps the counter and its operating mechanism in place thereon.

The location of the counter on the paring machine is chosen with relation to the path of the sliding rod as it is swung on the rotation of the frame 2. The most suitable position on the type of machine illustrated in Figure 1 of the drawing is in front so that the slightly rearwardly curved lever 13 projects into the path of the sliding rods of the rotating forks. For every revolution of the rotating frame 2 the counter should therefore be operated twice providing an apple is placed on each of the forks, 1, 1. If only one apple is placed on the forks during the

revolution the counter is operated but once, and if no apple is placed on the forks during the revolution the counter will not be operated at all.

From the foregoing it will be seen that only when an apple is placed on the forks of the paring machine will the counter be operated during the operation of the apple paring machine. A true count of the actual performance of the machine and its operator is thus made possible without having to actually watch the work of the operator.

We claim:

In an apple paring machine having a frame and having a plurality of forks, and having a rod mounted to slide within each of said forks and normally contained therein and having a rotating frame carrying said plurality of forks, said sliding rods being adapted to be forced out of the rear end of said forks when an apple is placed on the opposite end thereof, a U shaped bracket, a counter mounted on said bracket, a lever for operating said counter, means for supporting said U shaped bracket to place said counter, operating lever into the path of the projected ends of said sliding rods.

In testimony whereof we affix our signatures.

GEORGE B. FOX.
JOE G. CHRISTIAN.
